UNITED STATES PATENT OFFICE.

CHARLES KAUFMAN, OF SANTA ANA, CALIFORNIA.

DESIGN FOR AN ELECTRIC BRACKET-LAMP.

46,569.

Specification for Design.

Patented Oct. 20, 1914.

Application filed August 10, 1914. Serial No. 856,151. Term of patent 3½ years.

To all whom it may concern:

Be it known that I, CHARLES KAUFMAN, a citizen of the United States, residing at Santa Ana, in the county of Orange and State of California, have invented a new, original, and ornamental Design for Electric Bracket-Lamps, of which the following is a specification, reference being had to the accompanying drawing, forming part thereof.

The figure is a perspective view of an electric bracket lamp.

I claim:

The ornamental design for an electric bracket lamp, as shown.

CHARLES KAUFMAN.

Witnesses:

D. N. KELLY,
H. H. DALE.
